UNITED STATES PATENT OFFICE.

HIRAM H. SPONENBURG, OF GURNEE, ILLINOIS, ASSIGNOR TO OTTO R. BARNETT, OF CHICAGO, ILLINOIS.

RAIL-ANCHOR.

1,123,610.

Specification of Letters Patent.

Patented Jan. 5, 1915.

Application filed May 8, 1914. — Serial No. 837,273.

To all whom it may concern:

Be it known that I, HIRAM H. SPONENBURG, a citizen of the United States, residing at Gurnee, in the county of Lake and State of Illinois, have invented certain new and useful Improvements in Rail-Anchors, of which the following is a specification.

My invention relates to a device for preventing the longitudinal creep of railroad rails, such devices being commonly called rail anchors, rail stays or anti-creepers; and the invention has for its primary object to provide an anti-creeping device which will be inexpensive to manufacture, light in weight, easily applied to the rail and which, when in operative position will effectively maintain its hold upon the rail under varied conditions.

The invention has for a specific object to provide a new and improved form of rail anchor in which one of the parts consists of a spring which is put under stress when the device is applied to the rail so as to absorb looseness due to unequal expansion and contraction of the rail and the parts of the anchor resulting from temperature changes, and so as to prevent the relatively movable parts of the device from being shaken loose due to the vibration of the rail or otherwise, or from other causes disturbed from their operative relationship.

The invention herein disclosed has certain features in common with the invention disclosed in my co-pending application Serial No. 835,900 filed May 2, 1914. Whatever is common to the two applications is claimed in the application above referred to and is disclaimed herein.

The invention is illustrated, in certain preferred embodiments, in the accompanying drawings; wherein—

Figure 1 is a view, in elevation, of a rail anchor illustrating one typical form of the invention, the device being shown as applied to a rail illustrated in section; Fig. 2, a plan view of the parts shown in Fig. 1; Figs. 3 and 4, sectional views taken on lines 3—3 and 4—4, respectively, of Fig. 2; Fig. 5, a view, in perspective, of the spring member of the device; Fig. 6, a view, similar to Fig. 1, illustrating a modification; Fig. 7, a sectional view taken on line 7—7 of Fig. 6, and Fig. 8, a view, in perspective, of the

spring member of the device shown in the preceding two figures.

Like characters of reference designate like parts in the several figures of the drawings.

Referring to the drawings, 10 designates a railroad rail and 11 one of the cross ties on which the rail is supported.

The embodiment of the invention shown in Figs. 1 to 5 inclusive, is made up of a yoke 12 preferably formed with a small jaw 13 at one end engaging one edge of the base of rail 10 and at the other end with a larger jaw 14; and of a tie abutting element 15 which is provided with a spring member 16 formed so that normally it has a slight curvature from end to end. A notch or recess 17 is formed between the part of the element 15 bearing against the tie 11 and the spring member 16 which permits the spring member to extend over and bear upon the upper surface of the base of the rail.

The device is applied to the rail by placing the element 15, 16 in the position above described and then driving the yoke element as far up on the spring 16 as it will go. As the position of the element 15, 16 is fixed by its abutment against the tie 11 any tendency of the rail to creep increases the stress between the yoke and the spring member by a further movement of the yoke toward the tie. Preferably the rear end of the spring member 16 is formed with a tooth 18 which bites into the upper surface of the rail base.

A modified construction embodying the same general principle is shown in Figs. 7 and 8. The anchor in this case consists of a yoke 19 and a spring wedge member 20 which engages both the upper and lower surfaces of the rail base and is formed with a tie abutting flange 21. One of the plates forming the double-wedge or cuff member, preferably the upper plate 22, is bowed from end to end so that when it is placed upon the rail it stands up away from the upper surface of the base flange. The plate is compressed when the yoke 19 is driven in place. Preferably the inner edge 23 of the plate 22 bears against the upstanding web of the rail 10 and is formed at opposite ends with teeth 24 which bite into the rail when the plate is compressed by the yoke. The teeth 18 and 24 may, if desired, be set into

the rail base with a hammer after the anchors are in operative position on the rail.

While I have described my invention as embodied in certain preferred forms and constructions, modifications might be made without departure from the principle of the invention. Therefore I do not wish to be understood as limiting the invention to the particular arrangements, constructions 10 and devices shown and described except so far as certain of the claims are so limited by their express language.

I claim:

1. A rail anchor comprising a tie abutting element formed with a spring member adapted to bear upon the upper surface of the base of the rail, and a yoke which embraces the rail base and said spring member and puts the latter under stress.

2. A rail anchor comprising a tie abutting element formed with a spring member adapted to bear upon the upper surface of the base of the rail, and a yoke which embraces the rail base and said spring member and puts the latter under stress, said spring member being formed with a tooth which bites into the rail.

3. A rail anchor comprising a tie abutting element formed with a spring member adapted to bear upon the upper surface of the base of the rail, and a yoke which embraces the rail base and said spring member and puts the latter under stress, said spring member being formed with a tooth which bites into the upper surface of the base flange of the rail.

4. A rail anchor comprising a tie abutting element formed with a spring member adapted to project over the base of the rail, and a yoke which embraces said rail base and said spring and puts the latter under stress.

5. A rail anchor comprising a tie abutting element formed with a spring member adapted to project over the base of the rail and which is bowed up from the rail from end to end, and a yoke which embraces said rail base and said spring and puts the latter under stress.

6. A rail anchor comprising a tie abutting element formed with a spring member adapted to project over the base of the rail and which is bowed up from the rail from end to end and formed with a tooth adapted 55 to bite into the rail, and a yoke which embraces said rail base and said spring and puts the latter under stress.

7. A rail anchor comprising a tie abutting element formed with a spring member adapted to project over the base of the rail and which is bowed up from the rail from end to end and formed at each end with a tooth adapted to bite into the rail, and a yoke which embraces said rail and said 55 spring and puts the latter under stress.

8. A rail anchor comprising a tie abutting element formed with a spring member adapted to project over the base of the rail and to bear against the upstanding web of the rail, and a yoke which embraces said rail and said spring and puts the latter under stress.

9. A rail anchor comprising a tie abutting element formed with a spring wedge adapted to project over the base of the rail and to bear against the upstanding web of the rail, and a yoke which embraces said rail and said spring and puts the latter under stress.

10. A rail anchor comprising a tie abutting element formed with a spring cuff which extends around one edge of the base of the rail, and a yoke which embraces the rail base and said cuff.

11. A rail anchor comprising a tie abutting element formed with a spring cuff which extends around one edge of the base of the rail and bears against the upstanding web of the rail, and a yoke which embraces the rail base and said cuff.

12. A rail anchor comprising a tie abutting element formed with a cuff which extends around one edge of the base of the rail and bears against the upstanding web of the rail, and a yoke which embraces the rail base and said cuff.

13. A rail anchor comprising a tie abutting element formed with a spring cuff which extends around one edge of the base of the rail, and a yoke which embraces the rail base and said cuff, said cuff being formed with a tooth adapted to bite into the rail.

14. A rail anchor comprising a tie abutting member provided with a wedge-formed spring cuff adapted to extend around one edge of the base of the rail and to bear against the upstanding web of said rail, and a yoke which embraces said rail base and cuff.

15. A rail anchor comprising a cuff which surrounds one edge of the base of the rail and bears against the upstanding web of said rail, and a yoke which embraces the rail base and cuff; one of said elements being provided with means for giving the device a fixed position in the road-bed against the tendency of the rail to creep.

16. A rail anchor comprising a spring cuff which surrounds one edge of the base of the rail and bears against the upstanding web of said rail, and a yoke which embraces the rail base and cuff; one of said elements being provided with means for giving the device a fixed position in the road-bed 120 against the tendency of the rail to creep.

17. A rail anchor comprising a spring cuff which surrounds one edge of the base of the rail, and a yoke which embraces the rail base and cuff and exerts a bending pressure 125

against the latter; one of said elements being provided with means for giving the device a fixed position in the road-bed against the tendency of the rail to creep.

5 18. A rail anchor comprising a spring wedge-shaped cuff which surrounds one edge of the base of the rail and bears against the upstanding web of said rail, and a yoke which embraces the rail base and cuff; one 10 of said elements being provided with means for giving the device a fixed position in the road-bed against the tendency of the rail to creep.

15 19. A rail anchor comprising a spring wedge-shaped cuff which surrounds one edge of the base of the rail and is formed with a tooth adapted to bite into the rail, and a yoke which embraces the rail base and cuff; one 20 of said elements being provided with means for giving the device a fixed position in the road-bed against the tendency of the rail to creep.

25 20. A rail anchor comprising a tie abutting element formed with a spring member adapted to bear against the rail, and a yoke which engages the rail base and said spring member and flexes the latter.

30 21. A rail anchor comprising a tie abutting element formed with a spring member adapted to bear against a flat surface on the

base of the rail, and a yoke which embraces the rail base and said spring member and flexes the latter.

22. A rail anchor comprising a tie abutting element formed with a bowed spring member adapted to bear against a flat surface of the base of the rail, and a yoke which embraces the rail base and said spring member and flexes the latter.

35 23. A rail anchor comprising a tie abutting element formed with a bowed spring member adapted to bear against a flat surface of the base of the rail, and a yoke which embraces the rail base and said spring member and flexes the latter, said spring member 40 being formed with a tooth which bites into the rail.

45 24. A rail anchor comprising a tie abutting element formed with a bowed spring member adapted to bear against a flat surface of the base of the rail, and a yoke which embraces the rail base and said spring member and flexes the latter, said spring member 50 being formed at each end with a tooth which bites into said rail.
